EBER B. WHITE, OF SOUTH BEND, INDIANA, ASSIGNOR TO THE STUDEBAKER CORPORATION, OF SOUTH BEND, INDIANA, A CORPORATION OF NEW JERSEY

HOOD CLAMP

Application filed August 12, 1929. Serial No. 385,214.

This invention relates to clamps for vehicle hoods, the principal object being to provide a clamping means for the hood which will prevent movement of the hood in an upward or 5 outward direction and thus prevent rattling of the hood due to any movement relative to its fixed support.

Another object is to provide a clamp provided with a linkage having clamps carried 10 thereby adapted to exert pressure respectively on the side of the hood and a stationary part of the vehicle, such as the sill, to thereby firmly secure the hood against its fixed support when in closed position.

15 Another object is to provide a clamp adapted to be moved to inoperative position to allow ample space for the raising and lowering of the hood.

Another object is to provide a clamp with a 20 resilient pad adapted to bear against the side of the hood and a second pad adapted to bear against a stationary part of the vehicle, such as the sill, the pads being adapted to exert a pressure on the respective members and held 25 in such position under spring tension to prevent movement of the hood relative to its fixed support when in closed position.

These being among the objects of the present invention the same consists of certain features and combinations of parts to be herein-after described with reference to the accompanying drawing and then claimed, having the above and other objects in view.

In the accompanying drawing which illustrates a suitable embodiment of the present invention,

Figure 1 is a vertical fragmentary section of the hood, frame and fender showing the clamp for holding the hood in closed position 40 in full lines.

Figure 2 is an enlarged longitudinal sectional view taken on the line 2—2 of Figure 4.

Figure 3 is an elevational view looking in the direction of the arrows 3—3 of Figure 2.

45 Figure 4 is a top plan view of the hood clamp.

Figure 5 is a sectional view taken on the line 5—5 of Figure 2.

Referring to the accompanying drawing 50 in which like numerals refer to like parts

throughout the several views, the hood 1 is provided with a catch 2 secured to the outer side face thereof by means of the bolts 3. The catch 2 is formed to receive the hook hold-down or clamp portion 4 of the handle 5 of the manually operated hood clamp to be hereinafter described. A tubular shell 7 threaded at 8 into the handle 5 has a rod 9 inserted therein which is provided with a groove 10 adjacent to its upper end to receive the washer or abutment 11. A coil spring 12 interposed between the washer 11 and the bottom wall 13 of the tubular shell 7 is provided to maintain the hook 4 in proper engagement with catch 2 when the clamp is 65 in operative position. The rod 9 has a head 14 formed on the lower end thereof adapted to receive the pin 15 pivotally supported in one end of the link 16. The link 16 is pivoted at 17 intermediate its ends to a U-shaped stamping 18 which is pivotally mounted at 19 on the bracket 20 adapted to be secured to a stationary part of the vehicle, such as the sill 21, by means of the screws 22. A rod 23 pivoted at one end at 24 to the link 16 has a head 25 formed on the end thereof adapted to receive the clamp which may be in the form of a resilient pad 26 which is adapted to bear against the fender A or other stationary part of the vehicle, as is clearly shown 80 in Figure 1. The U-shaped member 18 has an upwardly extending arm 27 to which is secured a metal retainer 28 by means of the rivets 29. A side clamp 30, preferably a resilient pad, is supported by the retainer 28 85 and is adapted to bear against the hood 1 when in closed position, as is clearly shown in Figure 1.

When the hood 1 has been moved to closed position and it is desired to maintain the 90 same in that position to prevent rattling of the same, the operator grasps the handle 5 and moves the hold-down hook 4 over the catch 2 against the compression of the coil spring 12 positioned within the shell 7. When the hold-down hook 4 has been moved over the clamp 2 the spring 12 is held under compression and in so doing the rod 9 has been lifted causing the link 16 to pivot on the pin 17. 100

The movement of the rod 9 against the tension of the spring 12 thus causes the clamp 26 to be moved downwardly against the stationary part of the vehicle, such as the fender A, and at the same time the side clamp 30 is caused to move against the hood 1 due to the fact that the U-shaped bracket 18 is caused to pivot on the pin 19 thus causing the clamps 26 and 30 to bear against the stationary part of the vehicle and the hood respectively.

It will thus be seen that when the hood clamp is moved to operative position and the hold-down hook 4 is engaged with the catch 2 that the clamps 26 and 30 bear against the stationary part of the vehicle and the hood 1 respectively, thus exerting a pressure on these respective members due to the compression of the spring 12 to prevent rattling of the hood or movement of the same relative to its fixed support.

While I have shown one embodiment of my invention and have described the same in detail, it is to be understood that formal changes can be made therein as will be understood by those skilled in the art, and it is understood that my invention is not limited to the precise details shown, but that I desire to claim the same broadly as well as specifically, as is indicated by the appended claims.

What I claim is:

1. A vehicle hood-clamping device having, in combination, a hold-down clamp, a side clamp movable relative to said hold-down clamp movable into engagement with the hood, and a clamp movable into engagement with and pressing against a stationary part of the vehicle for maintaining said side clamp against movement when in operative position.

2. A vehicle hood-clamping device having, in combination, a hold-down clamp, a side clamp movable relative to said hold-down clamp movable into engagement with the hood, a link, and a resilient pad connected therewith movable into engagement with a stationary part of the vehicle for maintaining said side clamp against movement when in operative position.

3. A vehicle hood-clamping device having, in combination, a hold-down clamp including a sleeve, a link, a rod pivotally connected with said link arranged to slide within said sleeve, a pad pivotally mounted on said link and a second pad operatively connected with said first pad whereby said pads are caused to engage a stationary part of the vehicle and hood respectively when said hood-clamping device is in operative position.

4. A vehicle hood-clamping device having, in combination, a pivotally mounted member, a side clamp carried by said member, a link pivotally mounted on said member, a clamp carried by said link, and a hold-down clamp pivotally connected with said link whereby

engagement of said hold-down clamp with said hood will cause said side clamp to engage the side of the hood and said second named clamp to engage a stationary part of the vehicle.

5. A vehicle hood-clamping device having, in combination, a member pivotally mounted on a stationary part of the vehicle, a side clamp carried by said member, a link pivotally mounted on said member, a clamp carried by said link, a tubular shell, a hold-down hook on said shell, a rod slidable within said shell pivotally connected with said link, and a spring interposed between an abutment on said rod and an end wall of said sleeve tending to force said hold-down hook downwardly whereby when said hold-down hook is in operative position said side clamp and said clamp will bear against the hood and stationary part of the vehicle respectively.

6. A vehicle hood-clamping device having, in combination, a hold-down hook, a side clamp, and a clamp adapted to bear against a stationary part of the vehicle, said clamps being moved into operative position upon engagement of said hook with the hood.

Signed by me at South Bend, Indiana this 9th day of August, 1929.

EBER B. WHITE.
